UNITED STATES PATENT OFFICE.

GRANVILLE E. PALMER, OF BOSTON, MASSACHUSETTS, ASSIGNOR TO THE PALMER ELECTRIC & MANUFACTURING COMPANY, OF BOSTON, MASSACHUSETTS, A CORPORATION OF MAINE.

SERVICE SWITCH.

1,417,940.

Specification of Letters Patent. Patented May 30, 1922.

Application filed April 12, 1918. Serial No. 228,102.

To all whom it may concern:

Be it known that I, GRANVILLE E. PALMER, a citizen of the United States, residing at Boston, in the county of Suffolk and State of Massachusetts, have invented new and useful Improvements in Service Switches, of which the following is a specification.

This invention relates to electrical service switches, and has for its object to provide 10 certain improvements therein to ensure an accurate engagement and disengagement of the contact members, and also to secure a quick break upon the manipulation of the operating handle.

15 The invention comprises a switch having certain features of construction and arrangement which are illustrated upon the accompanying drawings, described in the following specification and pointed out in 20 the appended claims.

Referring to the drawings,—

Figure 1 represents in front elevation a switch mechanism embodying the invention, the cover of the case being removed to show 25 the interior.

Figure 2 is a similar view illustrating the slide in its closed position, being in part a section on the line 2—2 of Figure 3.

Figure 3 represents a longitudinal section 30 through the switch.

Figure 4 shows in detail the construction of the mechanism for moving the slide.

Figures 5 and 6 illustrate the operation of 35 the mechanism, the different positions of the parts being shown in dotted lines. These two views are as though taken on the line 2—2 of Figure 3.

Figure 7 shows in detail one of the stationary contacts of the switch.

40 The switch, which I have illustrated as an embodiment of the invention, is in many of its features identical with the service switch illustrated in the application of John A. Jessen, Serial No. 200,591, filed November 6, 1917, to which reference may be had for a detailed description of the parts to 45 which reference hereinafter will be but briefly made.

Of course it will be understood that the 50 terms which are herein used, such as "front," "rear," "top," "bottom," "sides," etc., are all intended in their relative senses and are not used in any limiting sense.

The mechanism is located within a case

which is preferably provided with a removable cover having a sliding door. The case is preferably made of sheet metal, as indicated as a whole at 10, and the removable cover is indicated at 11, being provided with the laterally sliding door 12 (see Figure 3). 55 Secured to the bottom of the box there is a removable plate 13 to which are attached the two blocks 14, 14, of slate, fiber or other insulating material. Upon these blocks are secured the stationary contacts 15, 15, with 60 which electrical conductors may be connected in any suitable way after being passed through apertures in the box which is preferably provided with the ordinary knock-out plugs commonly in use. I have illustrated the stationary contacts as being of the 65 spring-clip variety to engage knife members between the jaws thereof. Movable between the blocks 14 there is a slide comprising a plate 16 and a block 161 of insulating material, upon which are secured the movable 70 switch knife members 17, 17. These members are provided with spring clips 18 and are arranged in pairs so that they may be connected by the usual fuses not shown. To 75 prevent access to the current-carrying contacts 15, the slide is provided with the parallel side walls 19 of fiber or other insulating material and with a cross wall 20 of the same material. The walls 19, 19, are spaced 80 no further apart than the width of the opening which is closed by the sliding door 12. For the purpose of guiding the slide, the plate 13 is provided with upturned marginal portions 21 which are turned inwardly 85 as at 22 (see Figure 4) to form guideways for the down-turned side marginal portions 23 of the plate 16 which constitutes a portion of the slide. The slide is normally held 90 in its open position to the right, as shown in 95 Figures 1 and 3, by springs 24, 24, which have their rear ends attached to the plate 13 and their front ends attached to the plate 16 of the slide. The slide is moved to closed position against the tension of the springs, 100 and, as soon as the springs are able so to do, as will be explained, they quickly move the slide back to its open position. As thus far described, the mechanism does not differ 105 materially from that illustrated and described in the said application hereinbefore referred to.

The mechanism for securing the desired

movement of the slide will now be explained. It comprises a handle lever 25, having upon its end a knob 125. The hub of the handle is secured upon the upper end 5 of a spindle 26 which is journaled in the box and extends through the cover thereof, so that the handle may be secured upon its projecting end as by a screw 227 and washer 127. This spindle is connected with a crank 10 arm 33, as illustrated in Figure 3, and they are capable of a predetermined rotative movement one in relation to the other. Said crank arm has an axially extended hub 27 provided with an axial socket 28 at its upper 15 end to receive the lower end 29 of the spindle 26. The hub 27 is stepped at its lower end in an aperture in the base plate 13, and it is also mounted to rotate in an aperture in a plate 30 secured to an upright 31 attached to the upturned end of said plate 13. The spindle 26, in addition to being journaled at its lower end in the hub 27, is journaled in an inwardly projecting bracket 32 formed by bending the upper end of the 20 upright 31, and said spindle is also journaled in the hole in the cover through which its upper portion projects. To the crank arm 33 is pivoted one end of an elongated curved link or connection 34 by a pivot pin 35 to constitute therewith a toggle which may be brought into two dead-center positions alternately. The other end of the link 34 is pivoted by a rivet 37 to a lug 36 attached to the under side of the slide plate 16, 30 as shown in Figure 3. The crank arm 33 may be rotated through an arc of a little greater than 180° until it has just past a dead-center position as shown in Figure 5, the link 34 being curved to permit this movement. When the hub has been rotated to this position, it will be seen that the slide is locked by the toggle in its closed position with the movable contact 17 in mechanical and electrical contact with the stationary 40 contacts 15. By rotating the section or hub 27 anti-clockwise until the crank arm has been swung out of its said dead-center position, the springs 24 quickly move the slide to its open position, and this will occur upon release of crank 33 during any part of its movement clockwise until the crank arm has actually reached a dead-center position when the toggles are straight; and hence, in the second dead-center position, the slide is locked in its open position with the contacts separated. The hub 27 is provided with two separated stops or shoulders 38, 138, which are formed by cutting away a portion of the upper end thereof, and the spindle 26 is provided with a lug or pin 39 which may play between these two stops. As shown, the stops or shoulders are separated by an angle of about 120°, although this angle may vary. A coiled 50 spring 40 encircles the spindle 26, one end thereof being secured in a hole 41 in the upper end of the hub 27, and the other end of the spring bearing against a lug or projection 42 extending radially from the spindle 26. This spring exerts its tension upon the spindle 26 to rotate it clockwise so as normally to hold the stop pin 39 in engagement with the stop 38 on the hub 26. Consequently, if the handle be swung from the position shown in Figure 1 clockwise 70 through an arc of a little more than 180°, the pin or lug 39 engaging the stop or shoulder 38 will rotate the hub 27 and the crank arm 33 through an arc of 180° until the crank arm is moved from the position shown 75 in Figure 1 to the position shown in Figure 2. If, during this movement and before the crank arm reaches its dead-center position, the handle be released, the springs 24 will return the slide to its open position, and, 80 of course, rotate the operating spindle in a direction anti-clockwise through the spring 40. This is illustrated in Figure 6, in which the spindle is released when the parts have reached the positions indicated in full lines, 85 the positions indicated by the broken lines showing how the parts are resuming their normal positions with the slide open and the movable contacts disengaged from the stationary contacts. When the parts, however, 90 have reached the closed position with the toggle at a dead-center, the operating handle may now be swung anti-clockwise through a predetermined arc without affecting the slide. That is, the spindle 26 may be rotated 95 anti-clockwise until the pin or lug 39, after leaving the shoulder 38, engages the shoulder 138 (this being permitted by spring 40 which is not so strong as to prevent it), and continuing its movement rotates the crank 100 arm anti-clockwise out of its dead-center position, whereupon the slide will immediately snap open under the tension of the springs 24, and the crank arm and its hub will have a free rotative movement anti- 105 clockwise relatively to the spindle 26 until the stop shoulder 38 engages the lug or projection 39. Thus it will be seen that, while power is transmitted directly from the handle 25 to the slide (through the spindle 26, 110 the lug 39, the stop shoulder 38, the crank arm 33 and the link 34) to move said slide to open position, yet, when the handle 25 is moved anti-clockwise or in the opposite direction, it swings through an arc (determined by the distance between the shoulders 38, 138 and the width of the pin 39) without affecting the slide, and also that, when the stop or lug 39 engages the stop 138 and moves the hub 27 anti-clockwise through 115 a short arc until the crank arm has been moved out of its dead-center position, the lower section is thereafter rotated anti-clockwise independently of the spindle as the slide snaps open, thus making a quick 120

125

130

break. The opening movement of the slide, due to the action of the springs, 24, is assisted and accelerated by the action of the spring 40 which has had power stored 5 therein by the previous anti-clockwise movement of the spindle 26. The cover may have thereon the words Off and On, or words of similar import, located at the points at which the handle comes to a state of rest, 10 when the slide is in its respective open and closed positions. When the slide is closed or open, the spring 40 of course holds the handle in its "on" or "off" positions.

In connection with the upper part of a 15 section of the spindle, I preferably provide interlocking mechanism to prevent the handle from being operated when the door is opened and to prevent the door from being opened when the handle is in its closed 20 position, that is, when the switch has been moved to closed position. For this purpose, the upper part of the handle is provided with the member 43 for cooperation with the rib 44 on the door. I have not shown 25 these parts in detail as they are illustrated and described in the application hereinbefore referred to.

It may suffice to state that the member 43 is a disk having a flat face 43' on its 30 periphery which engages the flange or rib 44 extending inwardly along the lower edge of the door when the latter is open to hold the rock shaft against rotative movement and thus to lock the slide or carrier in open 35 position. When the door is in closed position and the rock shaft is rotated to move the carrier to closed position, an arcuate portion of the member 43 moves into the path of the flange or rib, as shown in dotted 40 lines in Figure 3, and thus locks the door in closed position.

There are numerous advantages incident 45 to the construction which I have illustrated and thus described which will be apparent to those skilled in the art. Among the chief of these advantages are that it is impossible for an operator to leave the switch only partly closed, because this cannot occur until the crank arm has been moved to a dead-center position where it locks the slide in its closed position; and that, as soon as the handle has been moved anti-clockwise sufficiently to move the crank arm out of its dead-center position, the slide snaps open 55 independently of the further rotative movement of the operating handle.

It is evident that various changes may be made in the particular structure which I have herein described without departing 60 from the spirit and scope of the invention as defined and claimed.

Having thus explained the nature of my 65 said invention and described a way of making and using the same, although without attempting to set forth all of the forms in

which it may be made or all of the modes of its use, what I claim is:

1. A service switch comprising a slide carrying movable contacts, a toggle including a straight link and a curved link arranged to move said slide in opposite directions to closed and open positions respectively, and, when in dead-center positions, to lock said slide in said open and closed positions, spring mechanism for automatically moving said slide to open position, an oscillatory member, and lost-motion means connecting said toggle and said member whereby said slide is operated in one direction to closed and locked position by 70 said member and said toggle, and said slide may be operated in the other direction to open and locked position by said spring mechanism independently of said member.

2. A service switch comprising a slide 85 carrying movable contacts, a toggle including a straight link and a curved link arranged to move said slide in opposite directions to closed and open positions respectively, and when in dead center positions to lock said slide in said open and closed positions, spring mechanism for automatically moving said slide to open position, an oscillatory member, lost motion means connecting said toggle and said 90 member, whereby said slide is operated in one direction to closed and locked position by said member and said toggle, and said slide may be operated in the other direction to open and locked position by said spring 100 mechanism independently of said member, and a spring normally holding said member at one limit of motion relative to said lost motion means.

3. A service switch comprising stationary 105 contacts, a slide arranged between said stationary contacts and having laterally projecting movable contacts, spring mechanism for moving said slide to open position, a crank arm, a curved link connecting said 110 crank arm to said slide and having a journaled hub, said link and arm constituting a toggle adapted in its dead-center positions to lock said slide in its closed and open positions respectively, and means for operating said crank comprising a spindle journaled in said hub, a handle thereon, coacting stops between the spindle and the hub of the crank arm to permit a limited play between them, and a spring coiled about said 115 spindle and having one end connected to said spindle and the other end connected to said hub.

4. A service switch comprising a closed 125 box or case, guides stationarily supported within the case, a slide adapted to reciprocate on said guides, laterally-projecting movable contacts on said slide, stationary contacts between which the slide is located and with and from which the movable con- 130

tacts may be connected and disconnected, spring mechanism for moving said slide to open position, a hub journaled in stationary bearings in the box and having an arm, a 5 curved link connecting the arm with said slide, said link and arm constituting a toggle which in dead-center positions locks the slide in its open and closed positions respectively, a rock-shaft projecting through 10 the front wall of the box, said shaft and hub having a lug and spaced stops, a coiled spring having one end secured to the shaft and the other end secured to the hub, and a handle located on said shaft outside the 15 front wall of the case, substantially as and for the purpose set forth.

5. A service switch comprising a closed box or case, guides stationarily supported within the case, a slide adapted to reciprocate on said guides, laterally-projecting movable contacts on said slide, a fuse on the front face of said slide in electrical engagement with said contacts, a movable door for said case positioned in front of said 20 fuse, stationary contacts between which the 25 slide is located and with and from which the movable contacts may be connected and disconnected, spring mechanism for moving said slide to open position, a hub journaled in stationary bearings in the box and 30 having an arm, a curved link connecting the arm with said slide, said link and arm constituting a toggle which in dead center positions locks the slide in its open and closed positions respectively, a rock shaft projecting through 35 the front wall of the box, said shaft and hub having a lug and spaced stops, a coiled spring having one end secured to the shaft and the other end secured to the hub, and cooperating members 40 on said hub and door for preventing the opening of said door except when said hub is in position to insure the disconnection of said movable and fixed contacts.

In testimony whereof I have affixed my 45 signature.

GRANVILLE E. PALMER.
